UNITED STATES PATENT OFFICE.

JOHN PURDY, OF NEW YORK, N. Y., ASSIGNEE TO THE MONARCH TYPEWRITER COMPANY, OF SYRACUSE, NEW YORK, A CORPORATION OF NEW YORK.

TYPE-WRITING MACHINE.

1,073,818.

Specification of Letters Patent. Patented Sept. 23, 1913.

Application filed July 19, 1912. Serial No. 716,352.

To all whom it may concern:

Be it known that I, JOHN PURDY, citizen of the United States, and resident of the borough of Brooklyn, city of New York, 5 in the county of Kings and State of New York, have invented certain new and useful Improvements in Type-Writing Machines, of which the following is a specification:

My invention relates to typewriting machines and more particularly to means by which work sheet holding devices may be readily detached from the machine so that, if desired, work sheet holding devices of a different character from those ordinarily 15 employed may be readily substituted for the devices on the machine.

In some typewriting machines such as the Monarch, for example, it is desirable to readily replace the ordinary paper holding devices, such as the paper fingers, margin feed rollers, etc., with other devices employed, for example, for billing work such as retail bill and charge work, or for card or stencil plate writing. It is likewise desirable to readily convert the machine into an ordinary correspondence machine by quickly replacing the ordinary paper fingers, etc., in the machine.

The main object of my invention is to 30 provide a simple and efficient construction by which the results specified above may be readily accomplished.

To the above and other ends which will hereinafter appear, my invention consists 35 in the features of construction, arrangements of parts and combinations of devices to be set forth in the following description and particularly pointed out in the appended claims.

40 In the accompanying drawings, Figure 1 is a fragmentary front elevation, with parts in section and parts omitted, of the carriage of a Monarch machine. Fig. 2 is an enlarged detail fragmentary top view, with 45 parts in section, of the connecting means for the supporting rod and some of the associated parts; the view illustrating parts as they appear when the supporting rod is locked in place. Fig. 3 is a detail fragmentary top view of the parts represented 50 in Fig. 2 but showing the parts as they appear when the rod is released for removal from the machine. Fig. 4 is a fragmentary top view of a modified form of the construc-

tion for supporting the rod at the right-hand end thereof.

I have shown my invention embodied, in the present instance, in a Monarch machine, but have merely represented so much of said machine as may be necessary to arrive at an understanding of my invention. It should be understood, however, that the invention may be embodied in various characters of typewriting machines.

55 The carriage comprises a rear guide bar 1 from which project forwardly extending end bars 2 and 3. These end bars are provided with bearings for a rotative platen 4 having a platen shaft 5. The right-hand end bar 3 of the carriage is provided with an upwardly projecting lug 6, apertured as at 7 for the reception of a reduced end 8 on one end of a supporting rod 9. The rod is arranged above the platen and extends throughout the length thereof, the opposite end of the rod being supported from the left-hand end plate 2 of the carriage in a manner to be hereinafter described. The supporting rod 9 supports the usual erasing plate 10 provided with ears 11 which are received in cut outs or circumferential grooves 12 in the rod near each end of the erasing plate. The ears 11 are bent around the reduced portions of the rod formed by the circumferential grooves, to connect the erasing plate to the supporting rod. The supporting rod in the present instance is provided with a spline groove 13 extending throughout, or substantially throughout, the length thereof and in which are received spring spline members 14 of the usual construction embodied in the Monarch machine and by each of which the associated paper finger support 15 is locked against turning movement on the supporting rod but is enabled to be adjusted longitudinally of the rod. Each support 15 has the usual forwardly projecting arm 16 fixed thereto and on this supporting arm is pivoted a carrier 17 for the margin feed roller 18 and a paper finger 19. The work sheet holding and controlling devices comprising the margin feed rollers, paper fingers and erasing plate thus far described are of the ordinary construction employed in the Monarch machine.

100 It is desirable to so construct the parts that the paper holding and controlling devices referred to above may be readily de-

tached from the machine in order that other work sheet controlling devices of a different character may be substituted therefor. In order to accomplish this result I have provided means for quickly detaching the supporting rod 9 together with the parts carried thereby from the machine. Thus, the left-hand end of the supporting rod 9 is provided with a tongue 20 which is adapted to be received in a corresponding groove 21 in the inner end of a supporting section 22. This supporting section in the present instance is in the nature of a short rod of a diameter corresponding to the diameter of the supporting rod 9. The section 22 is provided with a tongue 23 at its outer end, which tongue is adapted to be received in a corresponding groove 24 formed in an upwardly extending lug 25 on the left-hand end bar 2 of the carriage. The lug 25 corresponds to the lug 6 and is apertured to receive a headed screw 26, the threaded end 27 of which is received in a tapped opening in the supporting section 22. The unthreaded portion of the screw 26 passes freely through the usual nut 28 arranged outside of the lug 25. This nut is provided with an eccentric bearing portion 29 on which the usual toggle link 30 of the feed roll release mechanism is mounted. The nut 28 is effective to turn the eccentric bearing 29 to vary the pivotal point of connection of the link 30 and thus regulate the feed roll release mechanism. The screw 26 is effective not only to connect the supporting section 22 to the left-hand end plate but is likewise effective to secure the nut 28 in its adjusted position. The tongue and groove connection 23-24 between the carriage and the supporting section 22 is effective to prevent the supporting section from turning. It will be understood therefore that when the rod 9 has its tongue 20 seated in the groove 21 of the supporting section an interlocking connection will be established between the supporting section 22 and the rod 9, thus preventing a turning movement of the latter. In order to further connect the supporting rod with the section 22 I have provided a connecting or latching device or member which in the present instance is in the nature of a sleeve 31, said sleeve having a bore which corresponds to the diameter of the supporting rod 9 and the section 22. This sleeve is adapted to slide longitudinally of the supporting section and rod 9 into and out of a position where it will overlap or span the two members 9 and 22 as indicated in Figs. 2 and 3.

I prefer to employ means whereby the latching device or sleeve 31 may be locked or secured against accidental displacement when it is in the position shown in Fig. 2 to connect the supporting rod to the carriage. In the present instance I have provided a two-way slot 32-33, the portion 32 of the

slot extending longitudinally of the section 22 and the rod 9, whereas the portion 33 of the slot extends at substantially right angles to the portion 32. A pin 34 is fixed in the section 22 and projects into the slot 32-33. I preferably provide a finger piece on the latching device or sleeve in order to effect a turning movement thereof and to shift or slide it longitudinally on the supporting member 22 into and out of engagement with the supporting rod 9. This finger piece in the present instance consists of a pin 35 fixed to the sleeve and projecting outwardly therefrom.

As the parts are shown in Fig. 1 the supporting rod 9 is connected to the carriage and is fixed against rotative movement thereon, so that the spring pressure ordinarily exerted by the paper fingers and margin feed rollers may be rendered effective. If the operator desires to remove the supporting rod it is merely necessary to turn the sleeve with the aid of a finger piece 35 from the position shown in Fig. 2 to a position where the pin 34 will register with the slot 32. The sleeve may then be moved to the left on the section 22 as indicated in Fig. 3, thereby moving the sleeve out of engagement with the rod 9 and enabling the tongue 20 to be displaced from the groove 21, thereby freeing the left-hand end of the rod 9 from its supporting means. The rod 9 may then be moved to the left, withdrawing the bearing portion 8 from the bearing opening 7 in which it is seated. Thus, it will be understood that the supporting rod with the various paper controlling devices carried thereby may be readily removed from the machine and another corresponding rod equipped with work sheet controlling devices of a different character may be substituted therefor. When the machine is to be re-converted into an ordinary correspondence machine the rod 9 with the devices equipped as shown in the drawings may be returned to position and locked, connected with the carriage.

It will be understood that the left-hand end of the rod 9 abutting the section 22 prevents the longitudinal movement of the rod in one direction, whereas, the shouldered portion 36 of the rod at the junction between the body of the rod and the reduced portion 8 bears against the inner face of the projection 6 and prevents a longitudinal movement of the rod in the opposite direction. It will also be understood that the latching device when in the operative position shown in Fig. 2 constitutes a bearing for the left-hand end portion of the rod 9 which is seated in the bore of the sleeve.

In Fig. 4 I have illustrated a modified form of the construction in which the right-hand end of the supporting rod 9^a has a reduced portion 8^a which is received in a

corresponding opening in the end of a section 37. This section is secured in place to the right-hand end plate 3 of the carriage by a headed screw 38. The threaded end 39 of this screw is received in a tapped opening in the outer end of the section 37 in order to fixedly connect the section 37 with the carriage. The rod 9^a is otherwise constructed like the rod 9 and may be connected in a like manner by the means hereinbefore described for detachably connecting the supporting rod to the carriage at the left-hand end of the rod.

From the foregoing description it will be understood that I have provided simple and efficient means for detachably connecting the supporting rod 9 or 9^a to the frame of the machine; that the latching device may be readily manipulated to afford a quick removal of the supporting rod and the various devices carried thereby from the carriage or to quickly connect the same with the carriage.

It may be pointed out that in addition to facilitating an interchange of various characters of controlling devices the invention is also of value in facilitating the removal of a platen, when for any reason a platen is to be removed or a platen of one character is to be substituted for another.

Various changes may be made without departing from the spirit and scope of my invention.

What I claim as new and desire to secure by Letters Patent, is:—

1. In a typewriting machine, the combination of a carriage; a supporting rod that abuts at both ends with the parts by which it is supported in order to prevent a longitudinal movement of the rod; and means for detachably connecting the supporting rod to the carriage, said means comprising a latching device that is shiftable to connect the rod to the carriage or to release the rod and permit its removal from the carriage, and means for securing the latching device against accidental displacement from the position to which it may be shifted to connect the rod to the carriage.

2. In a typewriting machine, the combination of a carriage; a paper finger supporting rod; paper fingers carried thereby; and means for detachably connecting the supporting rod to the carriage, said means comprising a connecting member adapted to slide longitudinally of the rod and to constitute a bearing or rest for the rod at one end thereof, and means for securing the connecting member against movement longitudinally of the rod.

3. In a typewriting machine, the combination of a carriage; a supporting rod; and means for detachably connecting the supporting rod to the carriage, said means comprising a supporting section carried by the

carriage, a latching member movable thereon into and out of engagement with the rod to connect the rod to the carriage or to free it for removal from the carriage, and means for locking the latching member against accidental movement out of engagement with the rod.

4. In a typewriting machine, the combination of a carriage; a supporting rod; and means for detachably connecting the supporting rod to the carriage, said means comprising a supporting section carried by the carriage, said supporting section and rod abutting end-to-end, a sleeve mounted for movement longitudinally of said section and rod to span the two and connect them together or to free the rod to enable it to be removed from the carriage, and a pin and slot connection between said sleeve and one of said rod and section members to enable the sleeve to move longitudinally as specified or to lock the sleeve against such longitudinal movement.

5. In a typewriting machine, the combination of a carriage; a supporting rod; and means for detachably connecting the supporting rod to the carriage, said means comprising a supporting section carried by the carriage, said supporting section and rod abutting end-to-end, a sleeve mounted for movement longitudinally of said section and rod to span the two and connect them together or to free the rod to enable it to be removed from the carriage, said sleeve having a two-way slot therein, one portion of the slot extending longitudinally of the sleeve and the other portion at substantially right angles to the first mentioned portion, and a pin which is fixed to one of said section and rod members and which is received in said sleeve, whereby the sleeve may receive a movement longitudinally of the section and rod as specified and may be turned to lock the sleeve against such longitudinal movement.

6. In a typewriting machine, the combination of a carriage; a platen; a supporting rod arranged above the platen; paper fingers carried by and adjustable along said supporting rod; an erasing shelf likewise carried by said supporting rod; and means for detachably connecting the supporting rod with the carriage so that the supporting rod, paper fingers and erasing shelf may be removed as an entirety from the carriage when desired, said connecting means comprising a bearing for the rod at one end thereof and from which the rod may be withdrawn when it is released, a latching device at the other end of the rod, said latching device being shiftable to connect the rod to the carriage or to release the rod and permit its removal from the machine, and means for positively engaging the rod and preventing it from turning.

7. In a typewriting machine, the combination of a carriage; a supporting rod; means for detachably connecting the supporting rod to the carriage, said means comprising a sleeve that is movable longitudinally of the rod and is adapted to surround the rod at one end portion thereof; and transverse interlocking means coöperating with the rod to positively prevent it from turning.

8. In a typewriting machine, the combination of a carriage; a supporting rod; means for detachably connecting the supporting rod to the carriage, said means comprising a supporting section carried by the carriage, said supporting section and rod abutting end-to-end, and a latching member movable thereon into and out of engagement with the rod to connect the rod to the carriage or to free it for removal from the carriage; and means which interlock with the rod to prevent it from turning.

9. In a typewriting machine, the combination of a carriage; a supporting rod; means for detachably connecting the supporting rod to the carriage, said means comprising a supporting section carried by the carriage, and a sleeve mounted for movement longitudinally of said section and rod to span the two and connect them together or to free the rod to enable it to be removed from the carriage; and interlocking engaging means between the rod and said supporting section to prevent the rod from turning.

10. In a typewriting machine, the combination of a carriage; a platen; a supporting rod arranged above the platen; paper fingers carried by and adjustable along said supporting rod; an erasing shelf likewise carried by said supporting rod; and means for detachably connecting the supporting rod with the carriage so that the supporting rod, paper fingers and erasing shelf may be removed as an entirety from the carriage when desired, said connecting means com-

prising a bearing for the rod at one end thereof and from which the rod may be withdrawn when it is released, a supporting section carried by the carriage, a sleeve mounted for movement longitudinally of said section and rod and adapted to overlap the two to connect them together, and a pin and slot connection between said sleeve and one of said section and rod members to enable the sleeve to move longitudinally as specified or to lock the sleeve against such longitudinal movement.

11. In a typewriting machine, the combination of a carriage; a platen; a supporting rod arranged above the platen; paper fingers carried by and adjustable along said supporting rod; an erasing shelf likewise carried by said supporting rod; and means for detachably connecting the supporting rod with the carriage so that the supporting rod, paper fingers and erasing shelf may be removed as an entirety from the carriage when desired, said connecting means comprising a bearing for the rod at one end thereof and from which the rod may be withdrawn when it is released, a supporting section carried by the carriage, a sleeve mounted for movement longitudinally of said section and rod and adapted to overlap the two to connect them together, and a pin and slot connection between said sleeve and one of said section and rod members to enable the sleeve to move longitudinally as specified or to lock the sleeve against such longitudinal movement, said rod and section having one a groove and the other a tongue by which the rod is prevented from turning when the rod is in place.

Signed at the borough of Manhattan, city of New York, in the county of New York, and State of New York, this 18th day of July A. D. 1912.

JOHN PURDY.
